UNITED STATES PATENT OFFICE.

GENEVIEVE CRAWLEY THOMAS, OF OMAHA, NEBRASKA.

AUTOMOBILE-CAP.

1,115,615.

Specification of Letters Patent.

Patented Nov. 3, 1914.

Application filed February 18, 1914. Serial No. 819,327.

To all whom it may concern:

Be it known that I, GENEVIEVE CRAWLEY THOMAS, a citizen of the United States, residing at Omaha, in the county of Douglas and State of Nebraska, have invented certain new and useful Improvements in Automobile-Caps, which I designate Motor-Caps, of which the following is a specification.

10 My invention relates to automobile motor caps, and my object in this, my invention, is to provide ladies using automobiles with caps of becoming appearance and so made that they will be secured on the head without the use of pins, and by appliances that are integral parts of the cap, said appliances being so made that the cap will remain secure on the head, however swiftly the car moves, and despite gusts or strong 15 currents of wind. I accomplish such purpose by the means illustrated in the accompanying drawings, which are hereby made a part of this application, in which:

Figure 1 is an inverted perspective view 25 of the completed hat; Fig. 2 is a direct rear view in elevation, showing the expanded part of the hat; Fig. 3 is a rear elevation of the hat, properly trimmed, showing the veil loop at the rear of the head, with the 30 veil draped over the hat. Fig. 4 is a side elevation of the hat, as shown in Fig. 3, with the veil dropped over the face of the wearer of the hat.

In Fig. 2, the full lines show the initial 35 form of the hat, and the dotted lines show its form after expansion.

Like numerals refer to like parts throughout the several views.

Referring, then, to the drawings, 5 and 0 6 are the upper and lower curving wires, to which the head-band of the cap is secured. These wires are arranged parallel with each other, and at such distance from each other as to determine the width of the head-band. The wires do not extend entirely around the head, but have an open space at the rear of the cap. At the ends of the upper wire, the wire is curved downward, in the sections 8-8, which converge slightly; and these sections at their lower ends are turned to right and left respectively, and meet and are secured near to the respective cor-

responding ends of the lower wire. Thus a frame is formed upon which the head-band is secured. There is an open space 55 between the sections 8-8. At the lower and upper ends of these, elastics 10 and 10½ are secured, the former somewhat shorter than the latter, thus drawing the ends of these sections toward each other, causing 60 the converging effect.

Parallel to sections 8-8 are sections of wire, 9-9, which are secured to the upper wire, are then continued down to the lower circular wire, are there secured, and thence 65 are continued outwardly at nearly right angles a little distance, and then are again bent nearly at right angles and continued about the head-band, sloping upward until this wire becomes located about halfway between the upper and lower edges of the head-band, and stands a little outward from the same, the corners turning slightly downward. To this, and to the wire, 6, is secured crinoline, 11, or other suitable material, thus forming a rever. Upon the 70 head-band is secured the crown, 12, of crinoline or other suitable material.

At the upper end of the opening, that is, to the lower edge of the crown, or to the 80 material covering same, the strap, 13, is secured, being secured at its lower end also to the covering material. The veil, 14, is passed from the front of the cap around the head-band within the rever. It is secured 85 to the head-band or the rever part way around the cap beginning in front. When the cap is in use the veil is passed back under the strap and is there crossed and drawn forward and tied under the chin of 90 the wearer. The strap prevents the cap from being disconnected with the veil. When the veil has been secured about the cap, as above shown, of course its front fold can be passed over the face of the wearer 95 or the crown of the cap.

The head-band, rever and crown can be trimmed and adorned as taste may dictate.

Having fully described my invention, what I claim and desire to have protected by 100 Patent of the United States is:

In a motor cap, the combination of a head-band secured upon two parallel curved wires, a rever extending from the rear

having its ends secured to the head-band, a covering for the crown of the cap having a strap secured to its rear, and a veil secured to and passing backward between the head band and revere and under the strap, substantially as and for the purpose specified.

In witness whereof, I have hereunto sub-

scribed my name, at Chicago, Illinois, on the 10th day of February, A. D. 1914.

GENEVIEVE CRAWLEY THOMAS.

Witnesses:

MARIE GASKINS,
JNO. G. ROGERS.
